(57) CLAIM

The ornamental design for an assisted global positioning system apparatus, as shown.

DESCRIPTION

FIG. 1 is a front perspective view of the assisted global positioning system apparatus, showing my new design;

FIG. 2 is a rear plan view of the design;

FIG. 3 is a top plan view of the design;

FIG. 4 is a front plan view of the design;

FIG. 5 is a right side plan view of the design;

FIG. 6 is a bottom plan view of the design; and,

FIG. 7 is a left side view of the design.
